UNITED STATES PATENT OFFICE.

WILLIAM A. AINSWORTH, OF GRAND RAPIDS, MICHIGAN, ASSIGNOR OF ONE-HALF TO
CARL N. MATHER, OF GRAND RAPIDS, MICHIGAN.

DYEING COMPOSITION.

1,310,518.

Specification of Letters Patent. Patented July 22, 1919.

No Drawing. Application filed April 15, 1918, Serial No. 228,792. Renewed January 30, 1919. Serial No. 274,106.

To all whom it may concern:

Be it known that I, WILLIAM A. AINSWORTH, a citizen of the United States of America, residing at Grand Rapids, in the 5 county of Kent and State of Michigan, have invented certain new and useful Improvements in Dyeing Composition; and I do hereby declare the following to be a full, clear, and exact description of the invention, 10 such as will enable others skilled in the art to which it appertains to make and use the same.

This invention relates to a dye composition being particularly directed to a composition 15 of matter which may be applied to yarn, thread, or textile fabrics to dye the same and which when thus applied is instantly absorbed by the yarn, thread, fabric, or the like, dries immediately after application 20 thereto, and one which is fast and cannot be removed in any of the ordinary ways, such as by boiling the yarn or fabric to which the dye is applied, or even by treatment with acids. The composition is particularly effective 25 when used in conjunction with my previous invention on winding and dyeing machine, application for patent on which was made July 16, 1917, having Ser. No. 180,805, which invention is directed to a 30 means for dyeing yarn, thread, or similar fibrous material.

For an understanding of the invention and the ingredients which enter into the 35 composition, reference may be had to the following description in which the ingredients, the quantities used, and the manner of incorporating them, is disclosed.

To produce substantially one gallon of the dyeing composition, three-eighths of an 40 ounce of powdered dye of any preferred color is thoroughly mixed with five-eighths of a pint of glycerin so that the glycerin is thoroughly impregnated with the particles of dye. This is then diluted by the addition 45 of three-fourths of a gallon of denatured alcohol, to which mixture substantially one and three-eighths pints of water may be added. In practice a larger quantity than this is usually made at one time 50 and, for eight gallons of the dye composition, three ounces of dye, five pints of glycerin, six gallons of denatured alcohol, and

eleven pints of water are used, this being in the same proportion as that above outlined for the production of one gallon of the 55 dye composition.

A dye of this character, when thread, yarn or like fibrous material is brought into contact with it, is absorbed instantly, and this without the necessity of boiling or otherwise 60 treating the material to make it absorbent. As soon as it is absorbed it dries almost instantly, the alcohol evaporating with great rapidity, particularly when used and applied to a single continuous length of yarn, 65 thread, or the like as it is passing from one holder to another as outlined in my application for patent previously noted. The alcohol and glycerin in conjunction with the dye thoroughly dissolved in the same penetrates 70 yarns and threads or like fibrous materials instantly, the dye being carried entirely through the yarn, thread, or the like, while the volatile character of the alcohol permits the yarn or thread to dry almost 75 instantly. This is a feature of great importance, particularly when used in conjunction with my former invention.

The relative amounts of materials may be varied to some extent, particularly with respect to the dye, it being apparent that darker or lighter shades are produced by use of a greater or less amount of dye to the same amount of alcohol and water. A composition producing a certain shade may be 80 diluted with water and alcohol for lighter shades, the amounts of water and alcohol being substantially proportionate to the amounts used in the production of the composition. The water is not absolutely essential, but is of value in reducing the cost of 85 the composition as long as enough is not used to unduly dampen the yarn or like material.

I claim:

A composition of matter comprised of dye, glycerin, and alcohol in substantially the following proportions: three ounces powdered dye, thoroughly incorporated with five pints of glycerin and then diluted 100 with six gallons of alcohol, substantially as described.

In testimony whereof I affix my signature.

WILLIAM A. AINSWORTH.
